UNITED STATES PATENT OFFICE

117,116

DESIGN FOR A RADIO CABINET

Norman Bel Geddes, New York, N. Y., assignor
to Majestic Radio and Television Corporation,
Dover, Del., a corporation of Delaware

Application July 26, 1939, Serial No. 86,246

Term of patent 3½ years

To all whom it may concern:

Be it known that I, Norman Bel Geddes, a citizen of the United States, residing at New York, county and State of New York, have invented a new, original, and ornamental Design for a Radio Cabinet, of which the following is a specification, reference being had to the accompanying drawing, forming a part thereof.

The single figure in the drawing is a perspective view of a radio cabinet embodying my design.

The left hand end portion of the cabinet, which does not appear in the drawing, is a plain surface identical in appearance with that of the right hand end portion as shown. The rear portion or face of the cabinet which does not appear in the drawing is a plain surface.

I claim:

The ornamental design for a radio cabinet, substantially as shown and described.

NORMAN BEL GEDDES.
